Attorney

UNITED STATES PATENT OFFICE.

FRANK D. LEWIS, OF WEST ORANGE, NEW JERSEY, ASSIGNOR TO PATHÉ PHONOGRAPH AND RADIO CORPORATION, OF BROOKLYN, NEW YORK, A CORPORATION OF NEW YORK.

SOUND REPRODUCER.

Application filed August 30, 1923, Serial No. 660,166. Renewed March 8, 1927.

My invention relates to the art of sound reproducers and more particularly to a construction of loud speaker for reproducing with an extremely fine degree of purity the 5 electrical vibrations received in radio broadcasting.

One of the objects of my invention is to provide a loud speaker reproducer for operation upon a fair strength of signal, without 10 the requirement of a supplemental field, which is extremely faithful in reproduction of voice articulation and musical vibrations in the reception and reproduction of radio news, music, lectures and concerts.

15 Another object of my invention is to provide a loud speaker reproducer for operation with radio receiving apparatus with means for conveniently adjusting the relationship of the moving parts of the reproducer during 20 a period of actual operation from the exterior of the casing whereby an adjustment is obtained in conjunction with any particular radio receiving apparatus which will afford reproduction without distortion 25 and maximum enjoyment of the reproduced sounds.

A further object of my invention is to 30 provide a compact arrangement of mechanical parts including an electromagnet and pivoted armature for transforming electrical vibrations resulting in the reception of radio signals into sound vibration by reciprocal movement of a link member connected at 35 one end with the armature and at the opposite end with the apex of a conical diaphragm of the "Actuelle" reproducer type.

Another object of the invention is to provide 40 a removable receiver cup arranged in a frame supporting the conical diaphragm with a removable link connecting the apex of the conical diaphragm with a pivoted armature within the cup, the pivoted armature being positioned adjacent an electromagnet operating structure and adjusted 45 through a vernier movement controlled from the exterior of the cup for selecting the relative position of the conical diaphragm with reference to its peripheral supporting frame and the distance between the electromagnet 50 poles and the operating armature.

A further object of the invention is the provision of a receiver cup for driving an Actuelle type of reproducer, which cup contains an operating electromagnet reinforced

by a strong permanent magnet with an 55 armature adjacent the magnet poles and pivoted at one side on a substantially frictionless double bearing, each bearing adjustable from the exterior of the casing and guided at its opposite sides by means of a U-shaped 60 slotted resilient strip arranged to cooperate with the grooved head of a vernier screw, the screw passing through the receiver cup and controlled by a knob having means for locking the screw in any selected position 65 against rotation arising out of continued vibratory movement of said armature.

My invention will be more fully understood by reference to the accompanying drawings in which:

Figure 1 is a side elevation of an assembled loud speaker employing my construction of receiver cup and an Actuelle conical diaphragm carried in a peripheral frame 75 which supports the receiver cup in a spider concentric with the central axis of the cone; Fig. 2 is a rear view of my receiver cup assembled with the conical diaphragm showing the adjusting means on the exterior of the cup for selecting the position of armature bearings and fixing the relationship between the conical diaphragm and peripheral frame and the distance between the armature and magnet poles for securing the most pleasing tone quality of the radio 80 broadcast; Fig. 3 is an enlarged vertical cross sectional view taken on line 3—3 of Fig. 2; Fig. 4 is a vertical sectional view of the interior arrangement of the receiver cup taken on line 4—4 of Fig. 3; and Fig. 90 5 is a horizontal cross sectional view taken on line 5—5 of Fig. 4.

My invention employs an amplifying diaphragm of conical shape which is caused to vibrate piston like fashion within a peripheral supporting frame for the reproduction of the received radio broadcast at relatively large amplitude distributing the received broadcasting over a large area. I do not employ an additional field coil in this 95 reproducer such as has heretofore been required in many forms of reproducers with the inherent demand for an additional storage battery or the additional drain of the source of storage battery supply used for lighting 100 the electron tube filament circuits in the associated radio receiving circuits. With the advent of the dry cell type of electron tube 105

it has been impossible to use previous types of extra field winding loud speakers unless a storage battery were provided, and those types of loud speakers heretofore available 5 and operating without extra field coils have not satisfactorily reproduced the incoming energy with sufficient amplitude to render them desirable in lieu of a set of head telephone receivers. Head telephone receivers 10 are undesirable forms of reproducers in that they are inconvenient to wear and become tiresome to the listener, considerably reducing the enjoyment. The head telephone receivers are further objectionable in that a 15 number of head sets must usually be provided with an inherent diminution in signal strength as the number of head sets is increased.

Bearing in mind the disadvantages existent in prior types of reproducers I have 20 improved the construction of the loud speaker described in my copending application with Eugene A. Widmann, Serial Number 569,692 filed June 20, 1922 whereby 25 I am enabled to accurately adjust each loud speaker for operation upon any particular radio receiver to secure reproduction at good tonal quality without distortion and at large volume.

30 Referring more particularly to the drawings, numeral 1 indicates a peripheral circular frame supported on a standard and base 2 forming a support for the large conical diaphragm 3. The diaphragm 3 has an annular skirt portion 4 disposed at an angle with the surface of the cone and secured to the peripheral frame 1 by removable annular rim 1^a enabling a free piston like movement of the diaphragm within a limited dimension. A spider for supporting the receiver cup 5 is provided, formed of arms 6, 7 and 8 integral with the peripheral frame 1 and terminating in ring member 9. The receiver cup 5 is secured and set in ring member 9 by 45 means of set screws 10.

The receiver cup 5 is tubular in form having a portion of relatively small diameter fitting into ring member 9 and a portion 11 of relatively larger diameter which forms a housing for the electrical and mechanical operating mechanism of the loud speaker. A circular cover 12 having an annular skirt 14 fitting over casing 11 is provided on the rear of which the operating parts are mounted. 55 The skirt 14 is removably secured on casing 11 by means of screws 15.

60 On the rear of the cover 12 I arrange a pair of right angled pole pieces 16 and 17 having pole faces 16^a and 17^a and electromagnetic windings 16^b and 17^b contained thereon between flanges 16^c and 17^c. The pole pieces 16 and 17 are secured in position by permanent horseshoe magnets 18 and 19 through which screws 20 and 21 are passed from the front of the cover 12, and secured

by nuts on the other side of the permanent magnets. The electromagnetic windings 16^b and 17^b are connected in series and the ends brought out to terminals 22 and 24 which are well insulated from the receiver cup by insulating washers and bushings. Binding posts 22^a and 24^a are positioned on the outside of the receiver cup providing a convenient connecting means between the output circuit of the radio receiving apparatus and the electromagnetic windings. 70 75

I mount a bearing block 25 within the cover 12 adjacent the electromagnets. A double bearing is provided formed by slender screws 26 and 27 passing through bearing block 25, said screws being provided with slender grooved heads 26^a and 27^a accessible from the exterior of the casing in such manner that the screws may be adjusted into or out of the bearing block. The screws 26 and 27 terminate in finely ground point ends 26^b and 27^b which provide bearings for armature member 28. The armature member 28 is centered on the bearing points 26^b and 27^b and resiliently pressed thereagainst by means of adjustable screw 29 and coil spring 30. The weight of the armature is reduced to a minimum, thereby substantially eliminating mechanical inertia by reducing its dimension at 31. The end of the armature opposite the 85 pivotal mounting lies directly adjacent the electromagnet pole pieces 16^a and 17^a. A U shaped resilient strip 32 is secured by means of screw 33 to the end of the armature opposite the magnets. The strip 32 extends substantially beyond the electromagnets 16^b and 17^b and is provided with a central slot throughout a portion of each side of the U. An extended vernier screw 35 passes through a threaded bushing 36 in 90 cover 12 and is provided at the interior end with a grooved portion 37 and head 38. The U shaped strip 32 is arranged so that its slotted sides project on either side of the portion 37 and are confined within limits 95 of vertical movement by the shoulder 39 and head 38.

The rotative movement of screw 35 is controlled within predetermined limits by an arrangement of parts which cooperate 100 to maintain the screw member 35 in any particular position. Cup shaped annular rings 40 and 41 are provided concentrically positioned around screw member 35. A coil spring 42 is disposed between the cup rings 40 and 41 serving to constantly offer a friction grip between the inner surface of the hand knob 43 and the surface of the cover 12. A flat projecting arm 44 is secured adjacent the lower surface of the hand knob 43 by means of an integral annular ring. The hand knob 43 is properly located on the screw 35 and then set screw 45 tightened to lock the hand knob 43 in a selected position. A stop pin 46 is provided which 105 110 115 120 125 130 135 139

cooperates with the arm 44 to enable screw member 35 to be rotated within prescribed limits. The screw member 35 may be initially adjusted by means of screw slot 47.

5 The rotation of hand knob 43 not only selects the distance between the armature 28 and the pole pieces 16^a and 17^a but also serves to finely adjust the position of connecting link 48 which connects at its extremity with the apex 49 of the conical diaphragm 3. The electromagnetic mechanism within the casing 11 is protected by means of felt partition 50 across the circular extension 5.

15 In operation of the loud speaker it will be apparent that connection with the last stage of audio frequency amplification may be made through terminals 22^a and 24^a. The loud speaker is adjusted for reproduction at maximum tone quality first by longitudinally sliding the circular extension 5 backward or forward within ring member 9 until the desirable tension is secured on conical diaphragm 3 which is free to move within narrow limits by reason of the annular rim portion 4. When this desired position is obtained the electromagnetic mechanism is locked in this position by means of set screw 10. The armature 28 is located in 25 parallelism with the pole pieces 16^a and 17^a by adjusting the position of the bearing screws 26 and 27 by turning heads 26^a and 27^a. The armature tension is then adjusted by means of screw 29 and the link 48 attached and the complete electromagnetic mechanism inserted in the casing 11. The link 48 is then connected with the apex of the conical diaphragm at 49. The hand knob 43 may now be adjusted to finely regulate the distance between the armature 28 and the pole pieces 16^a and 17^a. It will be noted that all adjustments may be made 35 from the exterior of the casing during actual operation of the loud speaker.

40 45 While I have described my invention in certain limited embodiments, it is to be understood that modifications may be made without departing from the spirit of the invention and that I intend no limitations 50 upon the invention other than are imposed by the scope of the appended claims.

What I claim and desire to secure by Letters Patent of the United States is as follows:

55 1. A loud speaker for reproducing electrical vibrations comprising in combination a support, a circular frame carried by said support, a conical diaphragm peripherally mounted on said frame, a plurality of radial arms secured to said frame and terminating in a central ring, a receiver cup having a portion mounted in and slidably axially through said ring, electromagnetic operating mechanism carried by said cup, a link 60 extending through said cup portion and said

ring and connected at one end with said electromagnetic operating mechanism and at the other end with the apex of said conical diaphragm whereby vibrations imparted by said electromagnetic mechanism cause said 70 conical diaphragm to translate said vibrations into sound waves, and means for adjusting the position of said electromagnetic mechanism with respect to said diaphragm.

2. A loud speaker for reproducing electrical vibrations comprising in combination a support, a circular frame carried by said support, a conical diaphragm, an annular ring on said diaphragm secured in said frame, a plurality of integral radial arms 80 extending inwardly from said frame and terminating in a central carrying member, an electromagnetic operating mechanism having a portion mounted in and slidably axially through said central carrying member, and a link positioned in the line of the axis of said carrying member and connected at one end with said electromagnetic operating mechanism and at the opposite end with the apex of said conical diaphragm 85 whereby said electromagnetic operating mechanism may be fixed in position in said central carrying member to impart that degree of vibration to said diaphragm which affords reproduction of maximum tone 90 quality.

3. A loud speaker for reproducing electrical vibrations comprising in combination an electromagnetic mechanism having an 100 electromagnet, an armature, a pivoted bearing for one end of said armature, yieldable means constantly pressing said armature against said bearing, a resilient U shaped slotted strip secured to the opposite end of said armature, and a vernier adjusting screw 105 having means cooperating with said slotted U shaped slotted strip for selecting the position of said armature with respect to said electromagnet.

4. A loud speaker for reproducing electrical vibrations comprising in combination an electromagnetic mechanism having an 110 electromagnet, an armature, a pivoted bearing for one end of said armature, yieldable means constantly pressing said armature against said bearing, a resilient U shaped slotted strip member secured to the opposite end of said armature, and a vernier adjusting screw having a groove adjacent one end, 115 said groove having a length approximately equal to the distance across the sides of said U shaped member, said slotted U shaped member cooperating with said groove whereby the position of said armature relative to said electromagnet may be adjusted by rotating said screw.

5. A loud speaker for reproducing electrical vibrations comprising in combination an electromagnetic mechanism having an 120 electromagnet, an armature, a U shaped strip 125

- 4 having one side longer than the other, with said longer side secured along the center line to said armature at one end thereof, a double bearing for said armature at the opposite end thereof, one of said bearings disposed on each side of the center line of said armature, resilient means yieldably forcing said armature constantly against said bearings, and means cooperating with said U shaped strip for selecting the position of said armature with respect to said electromagnet for reproduction of electrical vibrations at maximum tone quality. 6. A loud speaker for reproducing electrical vibrations comprising in combination a support, a circular frame carried by said support, a conical diaphragm peripherally mounted on said frame, a plurality of radial arms secured to said frame and terminating in a central ring, a receiver cup having a circular casing, a circular extension on said casing of smaller diameter than said receiver cup, electromagnetic operating mechanism carried within said cup, a link extending through said circular extension and connecting said electromagnetic operating mechanism with the apex of said conical diaphragm, and means for selecting and fixing the longitudinal position of said circular extension within said central ring whereby to fix the tension between said diaphragm and said armature causing the electrical vibrations from said electromagnetic mechanism to be reproduced at maximum tone quality by said diaphragm. 7. A loud speaker for reproducing electrical vibrations comprising in combination a support, a circular frame carried by said support, a conical diaphragm peripherally mounted on said frame, a plurality of radial arms secured to said frame and terminating in a central ring, a receiver cup having a circular casing, a circular extension on said casing of smaller diameter than said receiver cup, electromagnetic operating mechanism carried within said receiver cup, a link extending through said circular extension and connecting said electromagnetic operating mechanism with the apex of said conical diaphragm, means in said central ring for locking said circular extension in a selected longitudinal position for fixing the tension between said armature and said diaphragm, and means operative from the exterior of said receiver cup for minutely fixing the tension between said diaphragm and said armature causing electrical vibrations from said electromagnetic mechanism to be reproduced at maximum tone quality by said diaphragm. 8. A loud speaker for reproducing electrical vibrations comprising in combination a support, a circular frame carried by said support, a conical diaphragm peripherally mounted on said frame, means carried by said support for centrally locating a receiver cup relative to said diaphragm, an electromagnetic mechanism including an electromagnet and an armature contained within said cup, a connecting link between said armature and the apex of said conical diaphragm, and spring pressed rotatable means operative from the exterior of said casing for adjusting the position of said armature relative to said electromagnet whereby electrical vibrations from said electromagnetic mechanism are reproduced by said diaphragm at maximum tone quality. 9. A loud speaker for reproducing electrical vibrations comprising in combination a support, a circular frame carried by said support, a conical diaphragm peripherally mounted on said frame, a receiver cup centrally carried by said frame and provided with a cover, an electromagnetic mechanism carried by said cover and portion of said cup including an electromagnet, an armature, a pair of pivotal bearings for one end of said armature, resilient means constantly and yieldably urging said armature in the direction of said electromagnet, a U shaped resilient member secured to the opposite end of said armature, a link connecting said armature with the apex of said diaphragm, and means extending through said U shaped member and said cover for adjusting the position of said armature with respect to said electromagnet, said pivotal bearings and said last mentioned means all being adjustable from the exterior of said cup for selecting that relationship of parts by which electrical vibrations are reproduced by said diaphragm at maximum tone quality. 10. A loud speaker for reproducing electrical vibrations comprising in combination a support, a circular frame carried by said support, a conical diaphragm peripherally mounted on said frame, a receiver cup centrally carried by said frame, an electromagnetic mechanism carried within said cup including an electromagnet, an armature, a pivotal bearing for one end of said armature, spring means pressing said armature against said bearing in the direction of said magnet, means exterior of said cup for adjusting the tension of said spring means, a U shaped slotted resilient member secured to the opposite end of said armature, a screw mounted in said cup having a groove adjacent the inner end thereof cooperating with said slotted U shaped member, and spring pressed means whereby said screw may be rotated from the exterior of said cup and positively held in a selected position for maintaining said armature spaced with relation to said electromagnet for reproduction of electrical vibrations by said diaphragm at maximum tone quality. 11. A loud speaker for reproducing electrical vibrations comprising in combination a support, a circular frame carried by said

support, a conical diaphragm peripherally mounted on said frame, a receiver cup centrally carried by said frame, an electromagnetic mechanism carried within said cup including an electromagnet, an armature, a pivotal bearing for one end of said armature, spring means pressing said armature against said bearing in the direction of said magnet, means exterior of said cup for adjusting the tension of said spring means, a U shaped slotted resilient member secured to the opposite end of said armature, a screw mounted in said cup having a groove adjacent the inner end thereof cooperating with said slotted U shaped member, a hand knob, and spring pressed means surrounding said screw exterior of said cup and disposed between said hand knob and said cup whereby said screw may be rotated from the exterior of said cup and positively held in a selected position for maintaining said armature spaced with relation to said electromagnet for reproduction of electrical vibrations by said diaphragm at maximum tone quality.

26 12. A loud speaker for reproducing elec-

trical vibrations comprising in combination a support, a circular frame carried by said support, a conical diaphragm peripherally mounted on said frame, a receiver cup centrally carried by said frame, an electromagnetic mechanism carried within said cup including an electromagnet, an armature, a pivotal bearing for one end of said armature a U shaped slotted strip secured to the opposite end of said armature, a screw threaded 30 adjusting member passing through said cup and slidably secured in said slotted U shaped strip, said member having a hand knob at its extremity exterior of said cup, flanges concentric with said member, a coil spring disposed between said flanges, and a stop for limiting the rotation of said member whereby said U shaped strip may be raised or lowered and positively set in a selected position 40 for fixing the position of said armature with respect to said electromagnet to enable electrical vibrations to be reproduced by said diaphragm at maximum tone quality.

In testimony whereof I affix my signature.
FRANK D. LEWIS.
